APPARATUS FOR STRAIGHTENING OUT DEFORMITIES IN MUDGUARDS

Hans Hou, Elmhurst, N. Y.

Application November 27, 1937, Serial No. 176,831

1 Claim. (Cl. 248—157)

This invention is for an apparatus, which has for its purpose to reshapen deformed mudguards, and the like, with respect to which it embodies new and useful improvements.

5 As the construction of my device is comparatively simple, the cost of manufacturing the same should be proportionately low.

With the above and other objects in view, this invention consists of the novel features of construction, combination and arrangement of parts, hereinafter fully described, claimed and illustrated in the accompanying drawing forming part of this application, and in which similar characters of reference indicate corresponding parts in

15 all views, and in which:

Figure 1 is a front elevation of my device.

Figure 2 is an enlarged side elevational view of a member forming part of my said device.

Figure 3 is a similar view, showing a cross bar 20 with an operating handle, also forming part of my said device.

Figure 4 is a front elevational view, showing a modification of my said device; while

Figures 5, 6 and 7 are detail elevational views 25 of parts, cooperating with my said invention proper.

Referring more particularly to the drawing, 10, 10 indicates the lower legs of my device; said legs are formed with hollow rectangular openings therein, as indicated at 11 in dotted lines, adapted to adjustably receive in a telescoping manner rectangularly shaped upper legs 12 therein; said legs 10 and 12, when adjusted, are relatively held together by means of bolts 13 inserted in openings 14 and 15 of said legs, respectively.

The lower legs terminate in enlarged feet 16.

One of the upper legs 12 is at its top formed with an enlarged portion 17; said portion 17 is 40 at its upper end made with a square opening 18 adapted to receive therein the square depending support 19 of a suitable member, or die 20; said latter member serving the purpose of an anvil as said member is placed below the deformed portion of the mudguard in the operation of smoothing or straightening out the deformity of the latter.

Said anvils, or dies may be of different shapes, such as shown in the Figure 5, 6 or 7, or of any 50 shape suitable to the special kind of automobile, which mudguards are to be straightened.

To the top part 17 is pivotally attached the other upper leg 12, as shown at 21.

Lugs 22 formed with openings 23 therein, as 55 shown in Figure 2, are by means of a bolt 30 se-

curely but turnably arranged upon each one of the upper legs, as shown in Figure 1.

A bar 24 is mounted in the openings 23 of the two lugs 22; said lugs and bar being relatively threaded in such a manner that when said bar 5 is operated by means of the handle 25 thereon, this bar may cause the legs 12, 12 to move towards or away from each other, and thereby raise or lower the apparatus accordingly.

An important object attained by the handle 25 10 is to the effect that the said handle may serve to manipulate, adjust and bring the apparatus in close contact with the deformity in the mudguard to be straightened out.

In Figure 4 the construction is somewhat like 15 that in Figure 1 with the exception that no bar is employed in connection with lugs; but the lower legs 10', 10' are hinged to a supports 26, 26, as shown at 27, while a bar 28 through said supports is adapted to raise or lower the structure, suitable threading of the supports and the bar being naturally provided for. The bar 28 may be operated by hand, or mechanically by means of an enlargement 29 upon said bar.

It is obvious that changes may be made in the 25 form, construction and arrangement of the several parts, as shown, within the scope of the appended claim, without departing from the spirit of the invention, and I do not, therefore, wish to 30 limit myself to the exact construction and arrangement shown and described therein.

What I claim as new, and desire to secure by Letters Patent of the United States, is:

A device of the class described, useful in the 35 process of straightening out deformities in automobile mudguards and comprising, a pair of lower legs formed with hollow rectangular openings therein, a pair of upper legs of a rectangular shape adapted to telescope within said lower legs, one 40 of said upper legs being formed with an enlargement adapted to hingedly receive the other one of said upper legs therein, said enlargement being made with a square opening in its top surface, whereby to receive a mudguard-shaping member, annularly-shaped members formed with threaded openings therein, and being pivotally secured to the upper legs, a bar threadedly mounted in said annularly-shaped members, whereby to move the legs towards or away from each other, 50 and a handle arranged upon said bar, whereby to operate the latter and manipulate the apparatus into close contact with the portion of the mudguards to be straightened.

HANS HOU. 55
